UNITED STATES PATENT OFFICE

CARY R. WAGNER, OF CHICAGO, ILLINOIS, ASSIGNOR TO GYRO PROCESS COMPANY,
OF DETROIT, MICHIGAN, A CORPORATION OF MICHIGAN

METHOD OF CONVERTING OILS IN VAPOR PHASE

Application filed August 21, 1928. Serial No. 300,998.

This invention relates to an improved method and apparatus for effecting the cracking of petroleum oils wherein such oils undergo molecular decomposition while they are maintained in a state of vapor, and the invention has particular application to the so-called high temperature systems of oil conversion which are utilized in the production of motor fuels or oils having a high anti-detonating value.

It is a primary object of the invention to provide in a system of this character a method of operation and accompanying apparatus so correlated as to secure maximum conversion of the oil vapors with minimum temperature fluctuation in such vapors during their passage through the conversion zone or elements of the system after a desired conversion temperature has been obtained.

It is also another object of the invention to provide for maximum conversions for each through-put of oil vapor through the converter with the use of relatively low temperatures and also to avoid employing relatively high temperature ranges, where the rate of reaction is so rapid that it is hard to control the system and where permanent gas is formed at a high rate.

For a further understanding of the invention reference is to be had to the following description and the accompanying drawings wherein Figure 1 represents a vertical sectional view taken through an oil converter formed in accordance with the present invention and Figure 2 represents a flow diagram showing the converter arranged with accessory apparatus.

Referring more particularly to the accompanying drawings, the numeral 1 designates an oil heater or converter of a type employed in connection with vapor phase methods of oil conversion. The heater is formed to include, in this instance, the customary walls or setting 2 in which is positioned a bank of converting tubes or elements 3. The interior of the converter may be heated by a fuel burner 4 so that appropriate operating temperatures may prevail in the converter. Oil vapor, obtained from any suitable source such as the vaporizer and evaporator shown in

Figure 2, enters the first pass of the converter tubes by way of the inlet line 5 at a temperature, for example, of 670° F., and these incoming vapors, while flowing through the first pass of the converter tubes, are subjected to the elevated temperatures of the converter so that the vapors quickly reach a conversion temperature in excess of 1000° F. In fact, when the vapors leave the first pass their temperatures approximate 1050° F.

I then pass the vapors through an elongated "soaking" or reaction chamber which in this instance is provided in the form of an elongated return bend 6, the internal area of which may be regulated to control the velocity of flow of the oil vapor therethrough either at equivalent or varying velocities with respect to the rate of flow of the vapors through the various tubes of the converter proper.

It is preferable to place a core of catalytic material such as ferrous oxide in one or more of the tubes 3 of the converter, the return bends, however, are preferably empty and devoid of contact or catalytic materials. From the return bends 6 the vapors travel through the second pass 3a of the converter and are again subjected to the heat of the converter, and from the pass 3a the vapors travel into a second elongated return bend 6a, disposed, like the bend 6, exteriorly of the setting and removed from direct exposure to the high internal temperatures of the converter. From the return bend 6a the vapors travel through the third pass 3b of the converter and thence through a third return bend 6b, arranged exteriorly of the converter walls and immediately below the return bend 6. From the return bend 6b the vapors travel through the fourth pass 3c of the converter in which they receive their final heat and are discharged from the converted by way of the line 7 for separation and fractionation in any desirable manner, such as, for example, by passing the same thru the fractionating tower and into the cracked oil tank, shown in Figure 2. It will be appreciated that the invention is not limited to the number of converter passes or return bends set forth, since the description

above given is merely one of explanation rather than one of limitation. The pass 3a may or may not be provided with a catalytic core, while preferably the tubes comprising the 5 passes 3b and 3c are empty or devoid of catalytic materials.

During the travel of the vapors through the tube or tubes of the first pass 3 the temperature of the vapors reaches approximately 10. 10 1050° F. and the return bend 6 is just large enough to permit endothermic reactions to go far enough to drop the temperature 20 to 50° F. in usually one to three seconds time. For example, the vapors enter the return bend 15 6 at a temperature of 1050° F. and leave the return bend at a temperature of 1020 F. During the travel of the vapors through the tube or tubes of the pass 3a their temperature is again raised from, for example, 1020° F. to 20 1050° or 1100° F., at which temperatures the vapors enter the second return bend or bends indicated at 6a. The return bends are preferably protected by heat insulation covering to reduce heat losses through radiation. 25

After passing through the return bend 6a the vapors enter the pass 3b at a temperature varying between 1000° and 1025° F. and enter the third return bend 6b at a temperature 30 varying between 1050° and 1100° F.

The vapors leaving the return bend 6b possess a temperature approximately of from 35 between 1000° and 1025° F., and after traversing the fourth bank of converter tubes 3c the vapors are discharged from the converter into a suitable cooling apparatus at a temperature, for example, of 1050° to 1100° F. This construction or method of operation provides alternate heating and "soaking" of 40 the oil vapors so as to secure maximum conversion with minimum temperature fluctuation or, in other words, to provide for an increased production of a motor fuel distillate for each through-put of material traversing 45 the converter. The process is also carried out, by the construction set forth, in such manner as to avoid going into very high temperature ranges, where the rate of reaction is so rapid that it is difficult to control, and 50 where permanent gas is formed at a high rate.

In vapor phase systems it is desirable to secure the highest per cent of motor fuel product obtainable with the least amount of permanent gas and also to obtain the highest 55 rate of conversion for each through-put of material through the converter. It is to the obtaining of these ends that the present invention is chiefly directed. Heretofore it has been customary to employ the shortest possible return bends between the various passes 60 of the converter tube banks, with the result that the temperature of the vapors passing through such tube banks is progressively increased from the inlet to the outlet end of 65 the converter. I have found that by employ-

ing the elongated return bends, which act as reaction or "soaking" chambers that improved temperature regulation is obtainable in the matter of avoiding excessive temperature fluctuation. In other words, the temperature of the vapors leaving the first pass of converter tubes is practically the same as the temperature of the vapors leaving the outlet end of the tubes 3c. The tube banks are so arranged that it usually required from 70 four to ten seconds for a given body of vapor to traverse the full length of the converter unit. This method of alternatingly heating the vapors and then providing the intermittent "soaking" chambers results in higher 75 conversion on a single through-put, which decreases fuel costs and increases the capacity of the apparatus without increasing the gas to gasoline ratio.

What is claimed is:

1. The process of cracking high boiling point hydrocarbons in the vapor phase which comprises vaporizing the hydrocarbons, separating the vapors from the unvaporized hydrocarbons, heating the vapors in a stream 90 to a cracking temperature, passing the vapors thru a zone wherein substantially only endothermic cooling occurs, again heating the vapors to a cracking temperature, and condensing and collecting the products. 95

2. The process of cracking high boiling point hydrocarbons in the vapor phase which comprises vaporizing the hydrocarbons, separating the vapors from the unvaporized hydrocarbons, heating the vapors in a stream 100 to a cracking temperature in the presence of a catalyst, passing the vapors thru a zone wherein substantially only endothermic cooling occurs, again heating the vapors to a cracking temperature, and condensing and collecting the products. 105

3. The process of cracking high boiling point hydrocarbons in the vapor phase which comprises vaporizing the hydrocarbons, separating the vapors from the unvaporized hydrocarbons, heating the vapors in a stream to a cracking temperature above 1000° F., passing the vapors thru a zone wherein substantially only endothermic cooling occurs to reduce the vapors to a temperature of not 110 lower than 1000° F., again heating the vapors to a cracking temperature, and condensing and collecting the products. 115

4. The process of cracking high boiling point hydrocarbons in the vapor phase which comprises vaporizing the hydrocarbons, separating the vapors from the unvaporized hydrocarbons, heating the vapors in a stream to a cracking temperature, passing the vapors thru a zone wherein substantially only endothermic cooling occurs without substantial concurrent formation of condensate, again heating the vapors to a cracking temperature, and condensing and collecting the 120 products. 125

5. The process of cracking high boiling point hydrocarbons in the vapor phase which comprises vaporizing the hydrocarbons, separating the vapors from the unvaporized hydrocarbons, heating the vapors in a stream to a cracking temperature, passing the vapors thru a zone wherein substantially only endothermic cooling occurs to a point above a critical temperature below which endothermic reactions cease, again heating the vapors to a cracking temperature, and condensing and collecting the products.

6. The process of cracking high boiling point hydrocarbons in the vapor phase which comprises vaporizing the hydrocarbons, separating the vapors from the unvaporized hydrocarbons, heating the vapors in a stream to a cracking temperature from 1000° F. to 1100° F., passing the vapors thru a zone wherein substantially only endothermic cooling occurs to reduce the vapors to a temperature of not lower than 1000° F. and without substantial interruption of the endothermic reactions taking place therein, again heating the vapors to a cracking temperature, and condensing and collecting the products.

In testimony whereof I affix my signature.
